US00D793967S

(12) **United States Design Patent** (10) **Patent No.:** **US D793,967 S**
Leeland et al. (45) **Date of Patent:** **** Aug. 8, 2017**

(54) **BUILDING CONTROL DEVICE**

(71) Applicant: **Honeywell International Inc.**, Morris Plains, NJ (US)

(72) Inventors: **Shanna Leeland**, Duvall, WA (US); **Philip Shen**, Redmond, WA (US); **Albert Holaso**, Bellevue, WA (US); **Eric Helzer**, Woodinville, WA (US); **Kevin Clinger**, Monroe, WA (US); **Maria Lalli**, Portland, OR (US); **Robert C. Frost**, Portland, OR (US); **Seonmee Kong**, Portland, OR (US); **Niklas Gustafsson**, Portland, OR (US); **J Matthew Baranauskas**, Portland, OR (US)

(73) Assignee: **Honeywell International Inc.**, Morris Plains, NJ (US)

(**) Term: **15 Years**

(21) Appl. No.: **29/562,769**

(22) Filed: **Apr. 28, 2016**

(57) **CLAIM**

The ornamental design for a building control device, as shown and described.

DESCRIPTION

FIG. 1 is a perspective view of a building control device in accordance with the present invention;

FIG. 2 is a front side view of the building control device of FIG. 1;

FIG. 3 is a right side view of the building control device of FIG. 1;

FIG. 4 is a left side view of the building control device of FIG. 1;

FIG. 5 is a top side view of the building control device of FIG. 1; and,

FIG. 6 is a bottom side view of the building control device of FIG. 1.

(Continued)

The portions illustrated in broken lines on the figures are for illustrative purposes only and form no part of the claimed design.

1 Claim, 6 Drawing Sheets
